[57] CLAIM

The ornamental design for a barbell weight or similar article, as shown and described.

DESCRIPTION

FIG. 1 is a front elevational view of a barbell weight or similar article showing my new design;
FIG. 2 is a rear elevational view thereof;
FIG. 3 is a side elevational view thereof;
FIG. 4 is a top plan view thereof;
FIG. 5 is a bottom plan view thereof;
FIG. 6 is a front elevational view of a modified embodiment of the design shown in FIGS. 1 through 5;
FIG. 7 is a rear elevational view thereof;
FIG. 8 is a side elevational view thereof;
FIG. 9 is a top plan view thereof;
FIG. 10 is a bottom plan view thereof;
FIG. 11 is a front elevational view of a second modified embodiment of the design shown in FIGS. 1 through 5;
FIG. 12 is a rear elevational view thereof;
FIG. 13 is a side elevational view thereof;
FIG. 14 is a top plan view thereof;
FIG. 15 is a bottom plan view thereof;
FIG. 16 is a front elevational view of a third modified embodiment of the design shown in FIGS. 1 through 5;
FIG. 17 is a rear elevational view thereof;
FIG. 18 is a side elevational view thereof;
FIG. 19 is a top plan view thereof; and,
FIG. 20 is a bottom plan view thereof.
